UNITED STATES PATENT OFFICE.

H. CLAY BASCOM AND CYRUS A. HODGES, OF TROY, NEW YORK, ASSIGNEES
TO SAID BASCOM.

DESIGN FOR A PARLOR-STOVE.

SPECIFICATION forming part of Design No. 15,400, dated September 16, 1884.

Application filed June 17, 1884. Term of patent 7 years.

To all whom it may concern:-

Be it known that we, H. CLAY BASCOM and CYRUS A. HODGES, citizens of the United States, residing in the city of Troy, in the county of Rensselaer and State of New York, have jointly invented and produced a new and original Design for Parlor-Stoves, of which the following is a specification, reference being had to the accompanying cut, print, or engraving illustrating said design.

This design embraces several new and distinct parts and combinations of parts which go to make up the whole design, as shown in the aforesaid illustration, and hereinafter specified.

The general shape of the main body portion of the stove is not new, the same being shown in Design Patent No. 13,513.

One distinguishing feature of this design is the configuration and ornamentation of the vase A, consisting of the base a, oval body b, having the ornament b', the flaring top c, and the ornamental brackets d.

Another feature is the ornamentation of the cover B, consisting of the upper part, f, having the single front row of open check-work ornaments f' and the lateral vine-form open-work ornamentations f'', and the lower convexly-curved portion, g, having the two united rows g' and g'' of arch-form open-work ornaments above the border h.

The ornamentation of the projecting panel of the upper front plate, C, consists of the upper corner ornaments, k, having the inclined bands k' and rows of upright pine-form ornaments k'', and the lower corner ornaments, l, having the inclined bands l' and the plant-form ornaments l'', all on the surface j', within the borders j i.

The configuration and ornamentation of the separable panel plate D consists of the four straight borders n, inclined to each other in the form of a rhomb, with intervening recessed rounded corners n', and the longitudinal name-band o, inclined ornaments o', and intermediate curved ornaments, o''.

The design for the front door, E, consists of the ornamented bead p' and floral ornaments q' on the curved upper part, p, having the mica lights g, and the bead and floral ornamenta-

tions s' on the lower portion, r, having the draft-apertures x.

The ornamentation of the end door, F, consists of the compound central ornament, t', and the corner ornaments, t' and t'', on the upper curved panel portion, t, above the parts u and u'.

The design for the end of the stove embraces the door F, having the ornamental parts t t' t'' and u u', the upper part, G, having an ornamental arch, the hearth H, and the lower portion, I, having the lower corner ornamentations.

The design for the legs J consists of the convexly and concavely curved portion v, the curved edge heading w, bead-ring x, floral ornament y, and the scroll-leaf ornaments z.

The whole design embraces the shape and ornamentation of the vase A, cover B, top plate below the cover, the front of the stove, including the plates C and D, the door E, and the intermediate hearth-plate, the end of the stove, embracing the parts G, F, H, and I, the bottom plate, and the legs.

We claim as new—

1. In a design for a stove, the configuration and ornamentation of the vase A, consisting of the parts a, b, b', c, and d, as set forth.

2. In a design for a stove, the open-work ornamentation of the cover B, consisting of the parts f f' f'' and g g' g'', as shown and described.

3. In a design for a stove, the ornamentation of the projecting panel of the upper front plate, C, consisting of the parts k k' k'' and l l'', as shown and described.

4. In a design for a stove, the shape and ornamentation of the panel-plate D, consisting of the parts n n' o o' o'', as shown and described.

5. In a design for a stove, the ornamentation of the front door, E, consisting of the ornaments p' and q' on the part p, and the ornaments s on the part r, as shown and described.

6. In a design for a stove, the ornamentation of the end door, F, consisting of the parts t t' t'', as described.

7. In a design for a stove, the shape and ornamentation of the end portion, embracing the parts G, F, H, and I, as set forth.

(OVR)

3. In a design for a stove, the shape and ornamentation of the legs J, consisting of the parts *x w x y z*, as shown and described.

9. The design for a stove, embracing the parts A and B, the top plate, the parts C, D, and E, and intermediate hearth-plate, the end parts, G F H I, the bottom plate, and the legs, shaped and ornamented as set forth.

In testimony whereof we hereunto set our hands, in the presence of two subscribing witnesses, this 14th day of June, 1881.

H. CLAY BASCOM.

CYRUS A. HODGES.
